(57) **CLAIM**

The ornamental design for a combined tiller head and joystick, as shown and described.

DESCRIPTION

FIG. 1 is a front perspective view of a combined tiller head and joystick showing my new design, as attached to a lift truck;

FIG. 2 is a front perspective view thereof;

FIG. 3 is a rear perspective view thereof;

FIG. 4 is a front perspective view of the joystick portion thereof;

FIG. 5 is a rear perspective view of the joystick portion thereof;

FIG. 6 is a front view thereof;

FIG. 7 is a rear view thereof;

FIG. 8 is a top view thereof; and,

FIG. 9 is a right side view thereof, the left side view being a mirror image.

The portions of the lift truck shown in broken lines in FIG. 1 are included for environmental purposes only, and form no part of the claimed design. The internal portions shown in broken lines in FIGS. 4 and 5 form no part of the claimed design.

The joystick is shown separated from the tiller head in FIGS. 4 and 5 for convenience of illustration.
